BRACKET FOR A TOWEL RING

Victor O. Anderson, 13153 Rivers Road,
Los Angeles, Calif. 90049

Filed Mar. 8, 1967, Ser. No. 6,116

Term of patent 14 years

(Cl. D4—3)

The broken line representation of a towel ring in FIGURE 1 is for purposes of illustration only.

I claim:

The ornamental design for a bracket for a towel ring, substantially designed as shown and described.
